UNITED STATES PATENT OFFICE.

FRANK T. FURGAL, OF WARREN, MASSACHUSETTS.

PICKER-STICK CONNECTION.

1,215,266.

Specification of Letters Patent.

Patented Feb. 6, 1917.

Application filed September 20, 1916. Serial No. 121,297.

To all whom it may concern:

Be it known that I, FRANK T. FURGAL, a citizen of the United States, residing at Warren, county of Worcester, State of Massachusetts, have invented a new and useful Picker-Stick Connection, of which the following is a specification.

This invention relates to the connections for operating a pickerstick and adjusting the power.

The principal objects of the invention are to provide a construction by which the device that operates the pickerstick can be connected with it at any desired height without perforating the pickerstick or boring into it in any way, and also at the same time to strengthen the pickerstick by the same means; to provide an improved form of buffer for engaging the edge of the pickerstick and imparting the blow thereto of such a nature that it can be formed from a used-up picker, thus greatly reducing its cost; and especially to provide one which will have a very long life in actual use.

Further objects and advantages of the invention will appear hereinafter.

Reference is to be had to the accompanying drawings, in which—

Figure 1 is a front elevation of a pickerstick with a preferred embodiment of this invention applied thereto;

Fig. 2 is a sectional view of the same on the line 2—2 of Fig. 1;

Fig. 3 is a sectional view on the line 3—3 of Fig. 1;

Fig. 4 is a sectional view on the line 4—4 of Fig. 1, and

Figs. 5 and 6 are views of a used-up rawhide picker showing how an element of this invention can be made therefrom.

The invention is shown as applied to an ordinary wooden pickerstick 10. This is provided near the top with two plates 11 having bolts 12 passing through them for securing them to opposite sides of the pickerstick, so that this element may be located at any desired height thereon. It is to be observed that by this construction the pickerstick does not have to be cut or bored into in order to secure this adjustment, and in fact the construction is such that the pickerstick is actually strengthened by this device, and I have used in practice a pickerstick split substantially throughout its length, and have found that this device will hold it to-

gether and permit it to operate at normal speed.

The two plates 11 are provided with a pin 13 extending between them beyond the edge of the pickerstick which pivotally supports what I call the power rod 14, a metallic rod by which the parts below are supported from the clamping device 11—12.

These parts below consist of the usual stick 15 and two metal plates 16 parallel with each other and adjustably connected with the stick 15 by a bolt 17. These plates are also secured together at the opposite ends by a bolt 18, and the pickerstick passes freely between them. The rod 14 is connected with them by a pin 19 as will be obvious.

Surrounding the bolt 18 is a rawhide buffer 20. This is shown complete in Fig. 6, and Fig. 5 shows in dotted lines the way in which this can conveniently be manufactured. It is taken from an old picker as 21, the usefulness of which has gone. This picker is made of rawhide and at its end has a passage therethrough for a well-known purpose. I find that in practice two of these members 20 can be cut from this picker, each one containing one of the original rivets 22 by which the two sides of the picker are held in ordinary practice. In this way a member is secured which consists of a single sheet of rawhide adapted to surround the bolt 18 and having its edges brought together and permanently united by the rivet 22. In this way the blow against the edge of the pickerstick is delivered by this rawhide member, and from the experience which I have had in using it I can say without reservation that such a member will ordinarily last for more than a year, whereas the devices which are ordinarily used for imparting this blow are of extremely short life and have to be replaced at frequent intervals.

The parts so far described virtually constitute the entire invention, but I have shown a plate 25 of leather shaped to cover the rear edge of the pickerstick and receive the blow from the member 20. This, however, is only for the purpose of properly spacing the parts in case of adjustment by moving the bolt 17 into another pair of holes in the plates 16.

By the use of the metallic clamping device 11—12 the desired adjustment of the

power is easily secured and the pickerstick is not only not weakened thereby, but it is materially strengthened as has been pointed out. Furthermore, the power rod 14 is a member which will last for long periods of time contrary to the usual power strap now employed, and it is so connected with the clamping device at the top and the plates 16 at the bottom that it will not bind or cramp 10 the parts in any way or rattle in practice. The durability of the member 20 has been described above.

It will be seen, therefore, that the entire device is made so as to last a long time and 15 avoid the constant repairs usually required for pickersticks and the usual connections for which these are substituted.

Although I have illustrated and described only a single embodiment of the invention, 20 I am aware of the fact that modifications can be made therein by any person skilled in the art without departing from the scope of the invention as expressed in the claims. Therefore, I do not wish to be limited to all

the details of construction herein shown and 25 described, but what I do claim is:—

1. The combination with a pickerstick, of driving means therefor comprising a transverse bolt arranged at the back of the pickerstick, means for operating the bolt, 30 and a rawhide member consisting of a portion of a used picker surrounding the bolt for delivering the blow to the edge of the pickerstick.

2. The combination with a pickerstick, of driving means therefor comprising a pair of plates spaced apart to receive the pickerstick between them, a bolt connecting them at the back of the pickerstick, and a raw- 40 hide member surrounding the bolt for de- livering the blow to the edge of the picker- stick, said rawhide member extending around the bolt and having its edges riveted together.

In testimony whereof I have hereunto set 45 my hand.

FRANK T. FURGAL.
